AUTOGRAPHIC REGISTER MACHINE

Mark B. Holmes and Arthur L. Rowland,
Utica, N. Y.

Application October 29, 1937, Serial No. 171,729

3 Claims. (Cl. 282—20)

Our invention relates to an autographic register machine and we declare the following to be a full, clear, concise and exact description thereof sufficient to enable anyone skilled in the art to which it appertains to make and use the same, reference being had to the accompanying drawings in which like reference characters refer to like parts throughout the specification.

The object of the invention is to produce a device in which the invoices or other business sheets of paper will travel in one direction and the carbon paper which is interlocked between said invoices will travel transversely to it.

Heretofore, in machines of this character the invoices were moved to give place to new or unused sheets by turning a hand crank which operated certain rollers for the purpose, whereas the carbon paper remained stationary. This was objectionable for the reason that the carbon paper became worn in certain places more than others before it was moved transversely by hand or was forgotten until past redemption.

The object will be understood by referring to the drawings in which,

25 Fig. 1 is a perspective view of the device showing certain parts swung into open position.

Fig. 2 is a detail enlarged view showing a certain pawl and immediate mechanism employed.

Fig. 3 is a perspective view of the device showing the parts in operative position.

Fig. 4 is a detail view showing a perspective of the operating mechanism employed.

Fig. 5 is a central vertical section taken on the line 5, 5 of Fig. 3.

35 Fig. 6 is a detail view showing a perspective of a modification.

Fig. 7 is an enlarged detail view showing a section of one of the arms employed.

Fig. 8 is an enlarged detail view showing a perspective of certain latch members and their immediate parts employed, portions being broken away.

Fig. 9 is an enlarged detail view showing a section of a socket for a plunger pin and of the plunger in full lines which is employed.

Referring more particularly to the drawings the device embodies a casing 1 having a cover 2 that is hinged on cross rod 3 which has bearings in the opposite sides 4, 4 of casing 1. The front end 50 is cut away at 5 to clear certain discs and a gear wheel hereinafter described. It rests on shoulders 6 that project laterally and are formed integral in the inside surfaces of sides 4, 4 of casing 1.

A second or over cover 12 is hinged at 13, 13 on 55 a rod 14 having bearings in the end members 15,

15 of auxiliary casing 16 which is attached or formed integral to the outer surface of one of the lateral sides 4 of casing 1. Cover 12 has a large opening at 17 above the surface of cover 2 which is therebeneath when in operating position, whereby 5 to allow for writing on the invoices 20 or other sheets of paper as they pass thereunder.

Shutters or partitions 25 are disposed transversely of casing 1 and adjacent the top edge thereof. Each of said shutters 25 is welded or 10 otherwise secured at their respective ends to the inside surfaces of sides 4, 4 of casing 1 and adjacent the top edge as above stated. Furthermore, said shutters 25 are inclined at an angle, whereby to direct the several sheets of paper 20 15 towards the front end of the machine and over the top surface of cover 2.

The means for drawing said sheets of paper 20 longitudinally of the machine embodies a master shaft 30 which has bearings in opposite sides 4, 4 20 of casing 1. Shaft 30 extends beyond side 4 and a crank handle 31 having boss 32 is mounted thereto and fixed to turn therewith by a set screw 33.

Discs 35, 35 having bosses 36, 36 respectively 25 are mounted to turn with master shaft 30 by means of set screws 37, 37. Plates 38, 38 with curved surfaces are formed integral in each instance to the periphery of discs 35, 35. Said plates 38, 38 cooperate with roller 40 thereabove and 30 hereinafter mentioned, whereby to draw paper sheets 20 longitudinally of the machine.

A spring pressed plunger 39 is mounted to stand upright in one of the discs 35 to engage the aligned apertures made in the successive layers of 35 paper 20, whereby to hold said sheets 20 in alignment.

Roller 40 is mounted to turn on shaft 41 which has bearings in elongated apertures 42, 42 formed in rock arms 43, 43 which are pivoted at 44, 44 40 to shafts projecting laterally from sides 4, 4 of casing 1. Said roller 40 is held yieldingly against plates 38, 38 of discs 35, 35 as they pass thereunder by coiled springs 45, 45 housed in apertures 42, 42 made in the free ends 47, 47 of rock arms 45 43, 43. Said springs 45, 45 press directly against plungers 48, 48 that rest also in said apertures 42, 42 in each instance and against the respective parts of shaft 41 adjacent its ends. Guard plate 49 bolted at 50, 50 to rock arms 43, 43 not only 50 covers the open ends of apertures 42, 42 but also ties said arms 43, 43 together, whereby they can be moved from full to dotted line position illustrated in Fig. 1. Furthermore, it acts as a guard to paper drawing mechanism heretofore de- 55.

scribed. The means for holding rock arms 43, 43 and the connected parts in full line position illustrated in Fig. 3 contemplates latch members 51, 51 which are fixed to turn on the outside of casing 1 to the extended ends of rock shaft 52 having bearings in the free ends 47, 47 of rock arms 43, 43. The free ends of latches 51, 51 are held normally in engagement with laterally projecting pins 53, 53 formed integral with the laterally projecting thickened portions 54, 54 of sides 4, 4 by a spring 55 coiled about shaft 52 and having one end 55 projected through said shaft 52 and the other engaging at 56 with a tight fit in a recess in the adjacent part of one of the arms 43. Ears 57 are formed integral with latches 51, 51 to aid in swinging said latches 51, 51 to full line position illustrated in Fig. 1.

The means for the turning of master shaft 30 in a clockwise direction embodies a gear 58 mounted to turn therewith and engaged by a pawl 59 pivoted at 60 to the inner surfaced one of the sides 4 of casing 1. Gear 58 also meshes with pinion gear 58' fixed to turn with shaft 41 carrying roller 40, whereby to insure the positive rotation of said roller 40 in cooperation with discs 35, 35.

The part that is new embodies the mechanism for drawing the carbon paper 61 transversely to the paper 20. This mechanism comprises a roller 62 mounted on shaft 63 having bearings in the ends 64, 64 of brackets 65, 65. Brackets 65 may be made integral with one of the walls 4 of casing 1 or bolted thereto by providing each with a wing 66 which is bolted or welded to the contiguous outside surface of side 4 of casing 1.

The means for turning roller 62 intermittently embodies the use of a ratchet wheel 67 having a boss 68 which is held to turn with shaft 63 by set screw 69. Ratchet 67 is engaged by a spring pressed pawl 70 mounted to turn on a shaft 71 carried on bearings in a vertically movable three sided casing 72. A spring 73 is coiled about shaft 71 and has one end engaging the rear of pawl 70 and the other held to the contiguous surface of casing 72. Casing 72 is mounted to slide within predetermined limits on one of the sides 4 of casing 1. To this end it is provided with elongated slots 74, 74 through which project headed bolts 75, 75 that engage the adjacent outer surface of one of the sides 4 of casing 1.

Casing 72 is held normally downward in full line position shown in Fig. 4 by a flat spring 76 secured at one end to block 77 formed integral or otherwise fixed to the adjacent side 4 of casing 1 and having its free end 78 resting on the top edge of vertically movable casing 72.

A friction reducing wheel 80 is mounted to turn on a shaft 81 having bearings in the lower part of casing 72. Said wheel 80 is engaged by a cam 82 fixed to turn with master shaft 30.

It will appear, therefore, that when the free end of cam 82 strikes wheel 80 on casing 72 it will elevate said casing 72 to dotted line position shown in Fig. 4, whereby pawl 70 will be likewise elevated to turn ratchet 67 the space of one notch. The turning of ratchet 67 will likewise rotate roller 62 to the same degree. A pressure roller 83 rests on roller 62 and cooperates therewith, whereby to draw the carbon paper 61 transversely across the machine when roller 62 and 83 turn. To this end roller 83 is mounted on shaft 84 which has loose bearings in the elongated recesses 85, 85 made in brackets 65, 65.

A supply shaft 86 is mounted in a removable manner in loose bearings formed in the ends 15,

15 of auxiliary casing 16 made integral with one of the sides 4 of casing 1 and directly opposite roller 62. Shaft 86 extends beyond one of the ends 15 of casing 16 to form a handle 91 for withdrawing shaft 86 from its bearings, whereby to load carbon paper 61 thereon. An enlargement at 92 will prevent shaft 86 from passing clear through its bearings.

A spring pressed plunger 95 mounted to a bearing at 96 in the adjacent side 4 of casing 1 projects into the path of rotating handle 31, whereby to limit said handle 31 to a single turn. Spring 97 resting in socket 98 and surrounding plunger 95 below shoulder 99 will urge said plunger normally outward. The means for holding cover 12 in closed position contemplates a latch member 100 having arms 101, 101 formed integral therewith. The upper ends of arms 101, 101 are rounded to form bearings 102, 102 for the projection of axle rod 103 which is carried in bearings 104, 104 made by bending over parts of the edge 105 of depending rim 106 made integral with cover 12. The upper edge 107 of latch 100 will engage nubs 108, 108 formed integral with the outside edges of brackets 65, 65. A handle 110 to aid in manipulating latch 100 is made from the same piece of metal and bent at an angle to said member 100.

Moreover, cover 12 is held above the top edge 111 of casing 1 by elevations or rests 112 made integral with said casing 1 and by the top edges 115, 115 of brackets 65, 65.

A plate 116 having notches 117, 118 thereon for clearing plunger 39 on one of the disc wheels 35 and gear 57 respectively is secured to the reduced portions 120, 120 of the upper edge 111 of casing 1. The inner edge 119 is bent upward slightly to direct the lowermost sheet or invoice 20 back into the interior of casing 1, whereas the sheets 20 above will slide over this plate 116 and pass out of the machine as it is used.

In operating the machine, the user will throw back roller 40 into full line position illustrated in Fig. 1. This can be done by manipulating ears 57, 57 of latches 51, 51 then throwing open cover 12 by manipulating handle 110 of latch member 100 to release said latch and then opening under cover 2. Paper rolls or stacks 20 are placed in the machine. The free ends of said rolls are fed severally up through shutters 25 and after lowering cover 2 forward over plate 116 with plunger 39 projecting upward through the holes in the aligned sheets 20. In the meantime, the several layers of carbon paper 61 will be unrolled from supply roller 86 sufficiently far to be drawn transversely through the several sheets 20 of ordinary paper and their ends caught between actuating roller 62 and pressure roller 83 thereabove.

Rock arms 43, 43 carrying roller 40 are swung back to full line position, whereupon latch members 51, 51 will automatically snap under pins 53, 53 to lock roller 40 in place yieldingly against the discs 35, 35 with the several sheets of paper 20 therebetween.

When the billing clerk is to make use of the machine, he will write the memoranda on the top sheet 20 which is transferred by the carbon paper 61 to the several sheets 20 therebeneath. After writing on top sheet 20 he will push in spring 70 pressed plunger 95 to clear handle 31. He thereupon releases plunger 95 and continues rotating handle 31 until it again comes into contact with stop plunger 95. The turning of handle 31 will cause discs 35, 35 and cooperating roller 40 to ro- 75

tate. This rotation of discs 35 and roller 40 will draw forward the sheets of paper 20 therebetween. The lowermost sheet 20 will be directed back into casing 1 through the opening just 5 below the turned up edge 119 of plate 116 for preservation and the other three directed towards the outside of the machine for distribution as shown in dotted lines in Fig. 5.

The turning of master shaft 30 will likewise 10 cause a simultaneous rotation of cam 82 fixed to turn thereon, whereby said cam will strike against the friction reducing wheel 80 in the lower part of casing 72. This will elevate casing 15 72 and pawl 70 carried therein, whereby to effect a partial rotation of ratchet 67 and of rollers 62 and 83. The rotation of rollers 62 and 83 will draw carbon paper 61 a predetermined distance transversely through sheets of paper 20 and thereby present a partial new surface between the new sheets 20 drawn thereover as above 20 described.

The modification shown in Fig. 6 contemplates the use of a machine where the paper is drawn manually over the plate 120' an under holding member 121 now to be mentioned. A spring 25 pressed holding member 121 is mounted above plate 120' and is connected with link 122 by pivot 123. Link 122 is pivoted at 124 to lever member 125 which is fulcrumed at 126 to a shaft projecting laterally from side 121 the springs for holding member 121 in upper or normal position are not shown.

When paper holding member 121 is pushed 30 down it will actuate lever 125 on its fulcrum 126 to push the casing 72 heretofore described upward, whereby to cause the spring pressed pawl 70 to turn ratchet 67 for rotating roller 62 as heretofore explained. Pressing downward on holding member 121 will pinch the paper 20 between the upper surface of plate 120' and the under surface of member 121.

In both forms of the device the carbon paper 35 61 passes between roller 62 and 83 and is torn off and thrown away.

Hereinabove the description stated that one of the sheets of paper 20 would pass beneath the edge 119 of plate 116, and pass into the casing 40 for preservation. However, in place of one of the

sheets passing within the casing all of the sheets 45 may pass above 116 and therebeyond for distribution.

Pressure roller 83 is mounted in the same manner as pressure roller 40 with the respect to 5 plungers 48, 48 and springs 45, 45. Plates 130, 130 hold springs 131, 131 within their respective recesses. Said plates 130, 130 are secured to the top edges 115, 115 of brackets 65, 65 by bolts or by welding.

Having thus described our invention what we 10 claim as new and desire to secure by Letters Patent is as follows:

1. In an authographic register machine, a master shaft having discs mounted thereon and turning therewith, a roller cooperating with said discs, whereby to draw paper therebetween, a cam mounted on said shaft, a pawl mounted adjacent said cam and actuated thereby, a ratchet engaged by said pawl, a roller turning with said 15 ratchet and a third roller cooperating with said roller turning with said ratchet, whereby to draw sheets of carbon paper therebetween.

2. In an autographic register machine, a master shaft, discs mounted on said master shaft, 25 means mounted on said discs to aid in aligning sheets of paper, a roller cooperating with said discs, whereby to draw said sheets of paper therebetween, another set of rollers for drawing carbon paper therebetween, a cam connected with 30 said shaft, a pawl actuated by said cam, a ratchet engaged by said pawl and said ratchet mounted to turn with said second named roller to draw the carbon paper transversely of said machine.

3. In an autographic register machine, a master shaft having discs mounted thereon and turning therewith a roller cooperating with said discs, whereby to draw paper therebetween, a cam mounted on said shaft, a spring pressed pawl 35 mounted adjacent said cam and actuated thereby, a ratchet engaged by said pawl, a roller turning with said ratchet and a gravity roller cooperating with said roller turned by said ratchet, whereby to draw sheets of carbon paper therebetween.
